(57) **CLAIM**

The ornamental design for a multi-tool, as shown and described.

DESCRIPTION

FIG. 1 is a perspective view of a multi-tool, showing my new design.

FIG. 2 is a top plan view thereof.

FIG. 3 is a bottom plan view thereof.

FIG. 4 is a left side view thereof; and,

FIG. 5 is a right side view thereof.

The broken lines in the drawings depict parts of the multi-tool that form no part of the claimed design.
